Des. 239,052
Patented Mar. 2, 1976

239,052

ELECTRIC GUITAR OR SIMILAR ARTICLE

Bruce J. Bolen, Lansing, and Edward Klein, Wilmette,
Ill., assignors to Norlin Music, Inc., Lincolnwood, Ill.

Filed Aug. 22, 1974, Ser. No. 499,574

Term of patent 14 years

Int. CL D17—03

U.S. CL D56—1 A

FIG. 1 is a front elevational view of an electric guitar or similar article showing our new design;

FIG. 2 is a left side elevational view;

FIG. 3 is a right side elevational view;

FIG. 4 is a rear elevational view;

FIG. 5 is a top plan view; and

FIG. 6 is a bottom plan view.

We claim:

The ornamental design for an electric guitar or similar article, substantially as shown and described.
